C. M. BERLIEN

STANDING VALVE

Filed Dec. 31, 1921

UNITED STATES PATENT OFFICE.

CORWIN M. BERLIEN, OF BURKBURNETT, TEXAS, ASSIGNOR OF ONE-HALF TO THE TEXHOMA OIL & REFINING COMPANY, OF WICHITA FALLS, TEXAS.

STANDING VALVE.

Application filed December 31, 1921. Serial No. 526,304.

To all whom it may concern:

Be it known that I, CORWIN M. BERLIEN, citizen of the United States, residing at Burkburnett, in the county of Wichita and State of Texas, have invented new and useful Improvements in Standing Valves, of which the following is a specification.

This invention relates to improvements in oil well apparatus, the general object of 10 the invention being to provide means for so arranging the standing valve that it will be free from obstructions and sand will be prevented from reaching the cups in the working barrel so that the parts will last 15 for a long time and the maximum production of oil will be secured at a minimum cost.

This invention also consists in certain other features of construction and in the 20 combination and arrangement of the several parts, to be hereinafter fully described, illustrated in the accompanying drawings and specifically pointed out in the appended claim.

25 In describing my invention in detail, reference will be had to the accompanying drawings wherein like characters denote like or corresponding parts throughout the several views, and in which:—

30 Fig. 1 is a sectional view through a portion of an oil well showing my invention in use.

Figures 2 and 3 are detail views of the invention.

35 In these views a casting 1 is shown having a central longitudinal bore 3 which merges into a large screw threaded socket 2 at each end. A perforated tubing 4 is threaded into the lower socket 2 and this tubing is connected with the anchor tubing 5. A smaller tubing 6 is threaded into the lower socket 3 and this tubing is the gas anchor. The tubing 6 passes through the tubing 4. A pipe 7 has its lower end screw threaded into the upper socket 2 and this pipe supports the working barrel 8. A smaller pipe 9 has its lower end screw threaded into the upper socket 3 and the upper end of this pipe sup-

ports the standing valve 10, the pipes 7 and 9 forming a chamber 11 into which sand and sediment will settle from the oil passing through the standing valve. This will prevent sand from reaching the cups in the working barrel and injuring them so that the improved device will work effectually 50 for a much longer time than where the standing valve is connected directly with the perforated tubing. The oil will pass through the perforated tubing so that it will be strained thereby before it passes into the 55 tube 6.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

In combination, a well casing joint for standing valves consisting of a casting having a central bore threaded at each end and provided between the threaded portions with an internal flange, said flange being of such thickness as to leave an opening of the same diameter as the internal diameter of suction and valve pipes fitting the threaded portions of the bore, said casting further having an internally threaded flange at each end adapted for connecting a well casing pipe, an imperforate well casing pipe screwed into the upper flange of the casting, a perforate well casing pipe screwed into the lower end of the casting, a standing valve pipe screwed into the upper end of the casting bore and butted against said flange, and a suction pipe screwed into the lower end of the casting bore and likewise butting against said flange whereby a smooth and unobstructed passage of uniform diameter throughout extends through the suction pipe, the casting and standing valve pipe, said casting being of uniform dimensions at each end.

In testimony whereof I affix my signature.

CORWIN M. BERLIEN.
